County Ohio.

Letters Patent

The Schedule referred to in this Letters Patent (and
making part of the same containing a description in the
name of the said Hugh Edgar and Isaac H. Edgar themselves
of their improvement in the portable Grain Thrasher)

To all to whom these presents shall come:

Be it known that we Hugh Edgar and Isaac H. Edgar
of Baugham Township in the County of Wayne and State
of Ohio have invented a new and useful improvement in
the portable grain Thrasher and that the following is a full
and exact description of the construction and operation of the
said portable Grain Thrasher as invented by us. The Horse
Power is constructed in the following manner No. two sills
14 feet long 6 inches wide 4 ins thick at one end and 3 ins
at the other are placed with the edge up 2 feet apart at
the largest end and about 2 ins apart at the small end,
a cross sill at feet long 10 ins wide and 4 ins thick is framed
in into the underside of the long sills 2 feet 2 ins from the
wide end and secured by screw bolts. Two other short
cross sills are framed into the long sills. The first is 4 by
6 ins in size and framed into the long sills 11 feet 3 1/2
ins from the wide end. The other same size framed in
with the edge up 5 feet 6 ins from the wide end of the long
sills. A crib piece is framed on the wide end of the long
sills about 3 feet long 4 ins thick and 10 ins wide with
the edge up let down one inch into the sills and secured
at each end by screw bolts passing up through both

another cross piece of sufficient length to extend to the outside of the long sills 3 in³ thick at the top and as much thick, or at the bottom, as the Buile may think necessary to brace against the action of the Housz. Same width framing into the Sills and secured in the same manner as the other. Two caps are framed on the top of these pieces, one on each side of the center longitudinal. They are about 6 feet 8 in³ in length 3 in³ thick 8 in³ wide above the center of the long cross sills and 6 in³ wide at each end let down into the cross pieces one inch and secured at each end by screw Bolts passing up through both. The main shaft is made of wood about 21 in³ in length and one foot square a step ledge of suitable size is inserted into the center of the lower end of the shaft which runs in a cast iron step, placed in the center of the long cross sill (before described) one foot of the lower end of the shaft is square to receive the master wheel, then a neck or journal 3 in³ long and nine in³ in diameter to receive the caps. The remaining 6 in³ of the shaft extends above the caps to receive the lower wheel, a circular aperture is cut in the caps one half in each 9 in³ in diameter which receives the journal on the main shaft made permanent by a screw bolt passing through the cap near the shaft. The shaft stands in a vertical position. The lower wheel is made circular about 2 feet 9 in³ in dia. made of 2 thicknesses of 1 1/2 or 2 inch planks, the grain of one thickness crossing the grain of the other and secured together with pins. A mortice 10 in³ square is made through the center to receive the top of the shaft. Large wrought iron staples are placed in this wheel to receive the lever to which the Housz are attached. The Housz attached to the lever from 9 to 10 feet from the center of the main shaft. The master wheel is made of 2 thicknesses of 1 1/2 inch plank and a rim 2 1/2 inches thick. The rim is 3 feet 10 inches diam.

ster, and 6 $\frac{1}{2}$ in. wide placed in the centre with the outer 1 $\frac{1}{2}$ inch of plank, on each side of the wheel filling a circle of 4 feet diameter except one half inch of the inner surface of the 14 $\frac{1}{2}$ in. plank on each side of the rim, which is cut to the size of the rim leaving one inch thick on each side of the wheel to project one inch beyond the rim which forms a groove to receive the segments of cast iron 3 $\frac{1}{2}$ in. thick, a mortise 13 in. square is made through the center of the wheel to receive the shaft and 4 pieces of timber the same thickness of the rim are placed round the mortise, and between the surfaces, and the whole firmly joined together in a permanent manner, the wheel is secured on the shaft in the usual way. The cast iron which surrounds the master wheel is put on in segments of one eleventh part of the circumference one inch thick and 3 $\frac{1}{2}$ in. wide and might be termed a curved plate with 5 equal sized and equal spaced mortises each mortise 14 $\frac{1}{2}$ in. in size across the plate or segment 14 $\frac{1}{2}$ in. on the outside and 3 $\frac{1}{2}$ of an inch in size on the inside of the segment length wise, secured to the rim by spikes passing through holes in the solid part of the segment and into the rim. The second shaft is of wrought iron 2 in. square one foot between the journals, the upper journal 2 in. long and 2 in. dia. and rung in a plummer box which is set into one of the caps (before described) and secured by screw bolts in the usual manner. The lower end is the same size and shape of the step bearing in the main shaft and rung in a step from the same pattern which is placed in the first short crob will (before described) on this shaft there is a pinion of cast iron 14 $\frac{1}{2}$ in. thick 7 $\frac{1}{2}$ in. diameter with 10 cogs made of suitable size and shape to work into the mortises described in the segment of the master wheel on the same shaft and below the

pinion there is a bevel wheel 28 in dia. which consists of a rim about $3\frac{1}{4}$ in wide made broad on the upper sides about $\frac{3}{4}$ of an inch thick at the verge and bevelled to an angle to suit the size of the pinion which is 8 in dia. giving it this form makes the rim considerably thicker in the made than at the verge and gives strength and proportion to the wheel. the bevelled face of this rim contains 50 mortises of equal size and shape about $2\frac{1}{2}$ in length across the rim and one inch in size in the centre lengthwise. the mortises extend through the rim but are less on the upper or bevel side which strengthens the space between them. the wheel is completed by a center and arms of proportional size.

A traveller $\frac{3}{4}$ of an inch thick and about 8 in dia. runs on the upper surface of the bevel wheel near the verge and above the bevel pinion. it revolves on an iron ax. le which is supported by the cross piece of the frame. The bevel pinion is 8 in dia. and 2 in thick with 16 cogs of suitable size and shape to work in the mortises described in the bevel wheel and is placed on the end of the line shaft. The line shaft is placed between the long sill from the last short cross sill to the small end about 7 feet long made of $14\frac{1}{2}$ inch square bar iron with 2 journals $14\frac{1}{2}$ in dia. and 2 in. in length. one of the journals on the end on which the pinion is placed and the other about 6 in. from the end both run in cast iron boxes. the end that projects beyond the box is made of suitable size and shape to receive the turning shaft. the small end of the sally made permanent by a iron bolt passing through them and confining them to the box which is set in between them. The machine consist of posts girts side pieces. Cope concave. fed. Cope concave upon cylinder. Cylinder Cope and spur wheels and pinions. There are 4 posts 2 of which are 3 in. thick by 14 in. wide the other 2 the

same thickness. 15 nos of the narrow ones of them 10 ins wide and the upper ends 8 ins wide. the sides of the posts glued to the back and front of the frame. There are 2 bottom side girts 2 feet 6 ins long between the posts. framed into them 8 ins from the bottom, one of them 2 by 6 ins in size is framed to the inside of the narrow posts. the other girt same thickness. one half of it same width and the other half 10 ins wide framed in 2 ins from the inside of the wide posts. the wide end glued to the front of the frame a side piece of the same dimension as the last named girt. is framed into the out edge of the wide post, the same distance from the bottom as the girts let into the posts one inch and secured to them with screw bolts. Two girts in which the concave is placed are framed into the posts one inch above the top of the lower side girts. they are 2 ins thick 3 $\frac{1}{2}$ ins wide at the front end and 16 at the back end and framed to the inside of the posts. the mortises which receive the back end made longer than the width of the lever to receive keys for the purpose of regulating the distance between the cylinder and concave to suit the different condition of the grain. The upper side girts are 3 by 4 in. in size framed to the inside of the posts 18 $\frac{1}{2}$ ins above and parallel with the enclosed surface of the concave girts. the upper side piece same size framed one inch into the outside of the wide posts. the surface of the side pieces has the same inclination and placed the same height as the upper side girts and secured to the posts with screw bolts. Two cross girts 2 by 3 in. in size are framed into the back of the frame one of them 3 inches from the bottom and the other 14. and one the same size framed into the front of the frame 3 ins from the bottom. Two caps are framed across on the tops of the posts one on the front and the other on the back which complete the frame. The front part of the frame 2 feet 6 ins and the back part 3 feet 2 in high. the concave is composed of 6 bars of $3\frac{1}{4}$ inch square bar iron and 3 bars of flat iron or wood 2 in wide. the square bars are placed with upper angles toward the centre of the cylinder. the horizontal angles placed

on a circle of 21 & $\frac{1}{2}$ in. dia. described from the centre of the cylinder on the inside of the concave gulf. The flat bars are placed with upper surface on the same circle and placed alternately between the upper bars. The shaft of the cylinder 18 $\frac{1}{2}$ in. square bar iron, 35 in. long, the shaft has 3 journals each 8 in. long and 18 $\frac{1}{4}$ in. dia. one on each end and one in the middle from one end and 2 in. from the other end, the long end to receive the cylinder and the short end receives a piston with which it is propelled. The cylinder is made with 3 heads or blocks one at each end and one in the middle made of 2 thicknesses of inch boards 18 in. dia. pinned together with the grain of one thickness crossing the grain of the other. A centre is made of cast iron of suitable size to fit the shaft with flanges on the outside, the centres extend through the heads, the flanges are fit into the outside of them, and the heads secured to the flanges with rivets. 8 bars of 5 $\frac{1}{2}$ square bar iron are placed equi-distant round the surface of the heads, with the angle cut projecting $\frac{1}{3}$ of an inch above the surface of the heads and 8 pieces of band iron 28 $\frac{1}{2}$ in. wide and $\frac{1}{4}$ of an inch thick are placed alternately between them they are so shaped that 1 $\frac{1}{2}$ in. of the width of them are placed with the flat side on the surface of the head, and the remaining inch of the width turned to project in a straight line from the centre of the cylinder and cut in the teeth square at the point wide and strong at the bottom of the projecting part of the bar. The teeth in one bar follow, the spaces in the other alternate, the teeth projecting $\frac{1}{3}$ of an inch above the square bars which make the cylinder 20 in. dia. a band of iron over all the bars at each end completes the cylinder. The centre of the cylinder is placed on the upper side gulf and side piece 16 in. from the back of the frame and is covered with a semicircular cap with an aperture in the front part of it through which the dust from the bottom is discharged. The feed spout is about 3 feet long. The lower end of it rests on the upper edge of the concave. The upper end is supported by

staples and hooks, connected with screw bolts through the ends of the back caps, so that the apron might be removed at pleasure, the concave apron extending from the front of the frame where the grain and straw are discharged. The Cylinder pinion is about 4 in dia, propell'd by a sun wheel 20 in dia which is placed on a shaft 5 in long between the journals. This shaft is placed on the wide part of the lower side Girt, and side piece of the frame dimensions about 13 in, from the front of the frame. There is also on this shaft a 5 in dia pinion which is propell'd by the ratchet wheel which is also 20 in dia and is placed on a 1 $\frac{1}{2}$ inch shaft which is 34 in between the journals, the journals each 2 in long and 1 $\frac{1}{2}$ in dia with about 4 in on the outside of the journals at each end made tapering (to receive the turning shaft) This shaft is hung on the lower side girt on one side and the narrow end of the lower side piece, on the other side and placed so as to work into the pinion on the short shaft. The machine is connected to the Horse power by a turning shaft, which is made of wood or iron as the builder may choose, if made of wood it is about 3 $\frac{1}{2}$ in dia, and about 10 feet long 2 pieces of iron half an inch thick are secured on each side of the shaft at the end with bands, and project 3 $\frac{1}{2}$ in beyond the wood with holes in the end to receive pins which are made on the angles of a piece of iron 3 $\frac{1}{2}$ in square and $\frac{3}{8}$ of an inch thick, another piece of iron 2 in wide, one inch thick in the middle, and thinner at the ends, a square hole is made in the centre to receive the ratchet wheel shaft or liner shaft with holes in each end 4 in from the centre to receive the pins on the contrary angles of the iron before described, the ends turned round and closed on the pins which completes the ratchet joint, both ends are made alike.

Improvements claimed— I claim as an improvement, the peculiarly simple and substantial construction of the frame of the Athol flour and Machine. The cheap and durable form of the master wheel, the propulsive shape of the head wheel which gives it

greater strength in proportion to the weight than the usual plan. The square pieces of iron with fins on the corners, in ratchet form which are easier made, more substantial, and work with less friction at a great angle, than those used heretofore. The form of the bar and the bar tooth cylinder, the teeth of which are not liable to fly out with the centrifugal force of the cylinder when in motion. Placing wood or flat bars between the square bars in the concave which leaves greater space for the grain and straw to pass. In regulating the concave to or from the cylinder with keys to suit the state of the ~~state of the~~ grain. The ratchet wheel shaft passing through the machine so that the tumbling shaft may be attached to either end to suit different situations placing half the gearing in the machine which reduces the motion of the tumbling shaft and simplifying the horse power.
